UNITED STATES PATENT OFFICE.

HENRY HAYWOOD AND GEORGE TOTTEN, OF TORONTO, CANADA; SAID HAYWOOD ASSIGNOR TO SAID TOTTEN; SAID TOTTEN ASSIGNOR OF ONE-FOURTH TO HARRY F. LOWE, OF SAME PLACE.

FENDER FOR CARS.

SPECIFICATION forming part of Letters Patent No. 601,961, dated April 5, 1898.

Application filed July 13, 1897. Serial No. 644,462. (No model.)

To all whom it may concern:

Be it known that we, HENRY HAYWOOD and GEORGE TOTTEN, of the city of Toronto, in the county of York and Province of Ontario, Canada, have invented certain new and useful Improvements in or Relating to Fenders for Street-Cars, Tram-Cars, and Railroad-Locomotives; and we hereby declare that the following is a full, clear, and exact description of the same.

This invention relates to certain new and useful improvements in that class of inventions known as "fenders," and is applicable to all classes of cars employed as street-cars, tram-cars, and railroad-service cars; and the object of the invention is to so construct the fender that it will be normally carried clear of contact with the rails or road-bed, and on meeting with an obstruction a leaf will be instantaneously dropped into close contact with the rails or road-bed in order that the obstacle will be gathered on and carried by the platform of the fender until the motion of the car can be stopped and the obstacle removed. By this means accidents to life and property can be avoided; and the invention consists, essentially, of two guide-rails rigidly connected temporarily to the under side of the car bottom or platform, a platform permanently connected to the bottom of the guide-rails, a drop-leaf hinged to the front end of the guide-rails, adapted to fall or be depressed into close contact with the car-rails when meeting with an obstruction, and a slideable locking-frame projecting beyond the front edge of the drop-leaf, adapted to normally hold the drop-leaf out of contact with the rails and road-bed, a latch to temporarily hold the slideable locking-frame in its normal position, and a spring to cause the sharp recoil of the slideable locking-frame, the whole device being hereinafter more fully set forth, and more particularly pointed out in the claims.

In the drawings, Figure 1 is a perspective view of the fender, showing the parts in their normal position and the drop-leaf out of contact with the road-bed. Fig. 2 is a similar view showing the position which the parts would assume when meeting with an obstacle. Fig. 3 is a detailed view of the drop-leaf.

Like letters of reference refer to like parts throughout the specification and drawings.

A represents the under side of the bottom of the car-platform, and B B represent two sleeves rigidly connected to the under side of the bottom, one located at each side of the platform.

C represents the frame of the car-fender, which is provided with two guide-rails c c in close proximity to the top of the car-rails. The inner side face of each of the guide-rails c c is provided with a guide-groove D, which extends from the front to the rear of the rails. The rails c c project from the under side of the car-platform to a proportionately considerable distance in advance of the car. Connected to the bottom of the guide-rails c c is a platform E. Hinged to the front of the guide-rails c c is a drop-leaf F, which extends entirely across the breadth of the car. The drop-leaf F is provided with two lugs f f, arranged one at each side of the drop-leaf and opposed to the end of their respective guide-rails c c. The interval between the under side of each of the lugs f f and the top of the drop-leaf F is equal in dimensions to that of the groove D. In other words, the said intervals form a continuation of the said grooves.

Connected to the hangers c' c' of the frame is a back G for the platform, the bottom of this back being located in the same plane as the top of the guide-rails c c, the top of the back being contiguous to the top of the hangers. The rear end of each guide-rail c is provided with a standard H, and journaled in the top of the standards H is a shaft I, on which is mounted two grooved pulleys J J. Connected to the middle of the shaft I is one end of a spiral spring K, while the opposite end of the spiral spring K is connected to the back G of the platform. Sliding in the grooves D D are the sides L of a horizontal frame. Connected to the rear end of the sides L L is a cross-bar M, which is provided with a forwardly-projecting arm N; the head n of the arm N being heart or leaf shaped. Connected to the cross-bar M are two cables O O', which are also coiled on their respective pulleys J J. The front end of the sides L L are united by a guard-rail O, suitably cushioned by rubber,

felt, or other suitable material. The guard-rail O extends beyond the front of the leaf F and is adapted to come into contact with the person or obstacle in the way of the advance 5 of the car before any other part of the fender, it being understood that the drop-leaf is an integral part of the fender.

The drop-leaf F is provided with a lock P, consisting of two pivoted tumblers *pp*, pressed 10 toward each other by springs Q Q. The tumblers *pp* are so arranged as to embrace the head *n* and hold the frame in its forward position. When the frame is in its forward position, the sides L L project under the overhanging 15 parts of the lugs *ff* and lock the drop-leaf in an elevated position and entirely clear of contact with the roadway or tracks. The guard-rail O on striking an obstacle forces the sliding frame rearward and the head *n* entirely clear of engagement with the lock P. The spring K causes the revolution of the shaft I and the pulleys J J to wind the cables O' O' upon their respective pulleys. The winding of the cables upon their respective 20 pulleys causes the frame to be drawn to the rear of the guide-rails *cc* to bring the guard-rail O against the hangers *c' c'* of the frame. The withdrawal of the sliding frame from the front of the guide-rails permits the drop-leaf 25 F to fall on the top of the tracks or road-bed, enabling it to scoop on the platform any obstacle or thing in the way of the advance of the car. The under side of the drop-leaf F is provided with a shaft R, on which are mounted 30 a number of rollers or wheels S, which are adapted to run on the top of the track or on the road-bed, as the case may be, the whole 35 operation being instantaneous.

Having thus fully described our invention, 40 what we claim as new, and desire to secure by Letters Patent, is—

1. A car-fender consisting of a platform, a drop-leaf hinged to the front of the platform, guides at the side of the platform, guides on 45 the hinged leaf in continuation of the platform-guides, a movable guard-rail sliding in the said guides, and when in its forward position adapted to hold the drop-leaf clear of contact with the rails or road-bed, substantially as specified.

2. A car-fender consisting of a platform, a leaf hinged to the front of the platform, a movable guard-rail at the front of the fender adapted to hold the hinged leaf normally clear 55 of the road-bed, and means for withdrawing the guard-rail to the rear of the platform when meeting an obstacle substantially as specified.

3. A car-fender consisting of a platform, a drop-leaf hinged to the front of the platform,

guides at the sides of the platform, guides on 60 the hinged leaf in continuation of the platform-guides, a movable guard-rail sliding in the said guides, and when in its forward position adapted to hold the drop-leaf clear of contact with the rails or road-bed, a lock carried by the drop-leaf to releasably hold the guard-rail in its forward position, substantially as specified.

4. A car-fender consisting of a platform, a drop-leaf hinged to the front of the platform, 70 guides at the side of the platform, guides on the hinged leaf in continuation of the platform-guides, a movable guard-rail sliding in the said guides, and when in its forward position adapted to hold the drop-leaf clear of 75 contact with the rails or road-bed, and means to cause the withdrawal of the guard-rail to the rear of the platform when meeting an obstacle, substantially as specified.

5. A car-fender consisting of a platform, a drop-leaf hinged to the front of the platform, 80 guides at the side of the platform, guides on the hinged leaf in continuation of the platform-guides, a movable guard-rail sliding in the said guides, and when in its forward position adapted to hold the drop-leaf clear of 85 contact with the rails or road-bed, a lock carried by the drop-leaf to releasably hold the guard-rail in its forward position, and means to cause the withdrawal of the guard-rail to 90 the rear of the platform when meeting an obstacle, substantially as specified.

6. In a car-fender, the combination of a platform, a drop-leaf hinged to the front of the platform, guide-rails at the sides of the 95 platform, and guides carried by the drop-leaf in continuation of the guide-rails, a sliding frame moving in the guides, and when in its forward position adapted to hold the drop-leaf clear of contact with the rails or road-bed, a lock carried by the drop-leaf, a bolt 100 carried by the frame, adapted to be engaged by the lock, a guard-rail carried by the frame, adapted to project beyond the drop-leaf when the frame is in its forward position, a shaft 105 journaled in suitable bearings mounted on the platform, drums carried by the shaft, flexible connections secured to the sliding frame, adapted to be wound on the drums, and a spring to actuate the said shaft, substantially 110 as specified.

Toronto, July 5, A. D. 1897.

HENRY HAYWOOD.
GEORGE TOTTEN.
